UNITED STATES PATENT OFFICE.

RUDOLPH M. HUNTER, OF PHILADELPHIA, PENNSYLVANIA, ASSIGNOR, BY MESNE ASSIGNMENTS, TO THE THOMSON-HOUSTON ELECTRIC COMPANY, OF BOSTON, MASSACHUSETTS.

ELECTRIC RAILWAY.

SPECIFICATION forming part of Letters Patent No. 426,382, dated April 22, 1890.

Original application filed September 23, 1886, Serial No. 214,309. Divided and this application filed May 15, 1889. Serial No. 310,855. (No model.)

To all whom it may concern:

Be it known that I, RUDOLPH M. HUNTER, of the city and county of Philadelphia, and State of Pennsylvania, have invented an Improvement in Electric Railways, of which the following is a specification.

My invention has reference to electric railways; and it consists of certain improvements, which are fully set forth in the following specification, and shown in the accompanying drawings, which form a part thereof.

This application, Case 96, is a division of my application, Serial No. 214,309, of September 23, 1886.

The invention relates to electric railways, in which a suspended conductor is arranged along the railway, and embodies an electrically-propelled car, having the electric motor or motors supported upon the axles preferably independent of the car-body, which rests on springs in the ordinary way, a collecting-arm preferably carried above the roof of the car and making a traveling contact with the under side of the conductor, and flexible or giving connections from the collector to the motor, including, if desired, the regulating apparatus and any electric translating device, which are desirably secured to the car-body. In this construction of railway I so construct the collecting device and suspended conductor that there is an automatic compensation for any variation in the altitude of either. It is immaterial what the details of construction may be, as any type of motor may be employed, and such motor may be supported by the axles or their boxes in any manner desired, so long as it retains its connection with the axle independent of the movement of the car-body, and any form of collecting device may be used which meets the requirements of the invention.

The object of my invention is to enable the motor or motors to have a positive connection with the axles, so as to remain in connection for positive-power transmission, as distinguished from chains and belts, (in which latter cases the motor is upon the car-body,) and at the same time provide a current-collecting device supported from the car-body and movable vertically therewith and having pro-

vision for maintaining a continuous contact with the suspended conductor. By this means the vertical movement of the car-body and its collector does not affect the perfect working of the motor and driving-gear, and where the conductor is suspended above the car the height of the car is utilized in reaching the conductor and allows of the collector being reduced to small size and weight. These are found of the utmost practical importance in the construction and operation of railways of this class. The flexible conductor-connections are carried by the car and connect the collector with the motor and include the regulator and allow for the rise and fall of the car-body in relation to the motor.

My object is also in such a railway to provide lighting and battery devices on the car-body with circuits to supply current from the conductors leading from the collector.

In the drawings, Figure 1 is a side elevation of an electric railway embodying my invention. Fig. 2 is a cross-section through the suspended conductor and shows the upper part of the collector, and Fig. 3 is a cross-section showing a modification of the collector applicable to my invention.

There are the posts arranged along the side of the railway-track A³, which may, if desired, form the return-conductor B.

The supply-conductor is B', and is suspended from the poles either by counterbalancing-arms B² or otherwise, as desired.

In Figs. 1 and 2 the conductor B' is normally suspended from above, so as to present a clean or unobstructed under surface for the collector wheel or shoe.

In the case of Fig. 3 the normal condition of the conductor B' is to rest in the V-shaped frames A³; but when raised by the collector-wheel C², as shown, it presents a clean or unobstructed under surface.

The collector-wheel C² is pivoted to the upper or free end of the upwardly-extending arm C', which may be made in any suitable manner and arranged vertically, horizontally, or at any other angle. In Figs. 4 and 5 this arm is shown as adjustable, and while indicated as pressing the collector-wheel upward against the under side of the conductor the

collector might be inverted and made to run in contact with the conductor if put at a lower elevation.

In my application of which this is a division the suspended conductor was shown as under the surface in a conduit, above the surface under the car, at an elevation, but not above the car-body, and also above the car-body.

10 The car-body C is supported on the axles by the usual springs I and is free to ride up and down upon the axles.

15 Carried upon the axles or their boxes is a frame D, upon which the motors D² are secured and by it journaled to the axles d. There may be one or two motors, as desired, and one may be used for each axle.

The car-wheels are marked D⁵.

20 On the axles d are secured worm-wheels D', with which worms D⁴ on the motor-shafts mesh.

Any other mechanical power-transmitting gearing may be used, if desired.

25 E E' E² are the motor-circuits on the car and include the reversing-switches E for each motor and resistance-changers e' e² for the respective motors.

30 The regulating apparatus is preferably supported on the car-body, as shown. These circuits form a flexible connection between the vertically-movable collector and the motors supported by the axles, and permit any vertical movement of the car-body without interfering with the electrical connection between the collector and motors.

35 In Fig. 4, R represents a regulator including the various switches, and may, if desired, include the resistance-changer e shown. The most flexible or giving circuits are preferably 40 those E' and E², extending between the motors and regulating apparatus.

45 G' is a lighting-circuit on the car and has the resistance-changer g, a switch, and the lamps G², which may be of any type. This is preferably in shunt or parallel relation with the motors.

50 E is a battery-circuit on the car and includes the secondary-battery cells F and a switch. This battery may be thus charged from the line and subsequently used for lighting the car or operating the motors on parts of the railway not supplied with conductors.

The arrows indicate the passage of the current.

55 Any other translating device may be connected in circuit with the circuit on the car between the collector and motors. It is evident that the motors may be independently controlled, if desired.

60 The collector-wheel may be simply a grooved wheel or other contact device suitable to the purpose. As shown it is in the form of a deeply-grooved wheel, in the groove of which the conductor fits and is guided, and the wheel in turn thereby guided on the conductor and following its direction.

65 It is evident that both the outgoing and

return conductors B' and B may be suspended (see dotted lines, Fig. 1) and two current devices be used to complete the circuit through 70 the car.

75 It will be seen that broadly considered the collector is supported on springs through the frame-work of the car-body and is free to rise and fall independently of the motors which are carried on the axles.

80 The current-regulating apparatus may be located or connect with either end of the car. The car may be run in either direction.

85 As before stated, I do not confine myself to the details here shown, as they may be modified in various ways without departing from the spirit of my invention.

90 In this application I do not claim the specific form of collector, arrangement of motors, or support of the conductor, as these matters form subject-matter of other applications—to wit, Serial Nos. 214,309, of 1886; 239,930, of 1887; 264,456, of 1888; 268,359, of 1888; 290,302, of 1888, and, 304,499, of 1889.

95 Any matters shown but not claimed are not dedicated to the public, but form subject-matter of said applications.

Having now described my invention, what I claim as new, and desire to secure by Letters Patent, is—

1. The combination of a railway-track, a suspended conductor arranged along said track, a car running upon said track, an electric motor supported upon the axle of said car, a current-collecting device carried by the car-body and making contact with said suspended conductor, a motor-circuit carried on the car-body connecting the collecting device with the motor, and current-controlling devices to control the current in said motor-circuit.

2. The combination of a railway-track, a suspended conductor arranged along said track, a car running upon said track and having its body supported on springs, an electric motor supported upon the axle of said car, a current-collecting device carried by the car-body and making contact with said suspended conductor, a flexible motor-circuit carried on the car-body, connecting the collecting device with the motor, and current-controlling devices to control the current in said motor-circuit.

3. The combination of a railway-track, a suspended conductor arranged along said track, a car running upon said track, an electric motor supported upon the axle of said car, a current-collecting device carried by the car-body and making contact with said suspended conductor, a motor-circuit carried on the car-body, connecting the collecting device with the motor, current-controlling devices to control the current in said motor-circuit, a translating device on the car-body, independent of the motor, and a circuit carried by the car connecting with the motor-circuit and coupling the translating device in multiple or shunt relation with the motor.

4. The combination of a railway-track, a suspended conductor arranged along said track, a car running upon said track, an electric motor supported upon the axle of said car, a current-collecting device carried by the car-body and making contact with said suspended conductor, a motor-circuit carried on the car-body, connecting the collecting device with the motor, current-controlling devices to control the current in said motor, a translating device on the car-body, independent of the motor, a circuit carried by the car, connecting with the motor-circuit and coupling the translating device in multiple or shunt relation with the motor, and separate circuit-controlling devices for the circuit of the translating device. 70
5. The combination of a railway, a suspended electric conductor arranged along the railway, a traveling car, an electric motor supported on and coupled with each axle, an upwardly-extending collector supported on the car-body, electric motor-circuits leading from the collector to each of the motors, and regulating devices for controlling the current flowing through the motor. 75
6. The combination of a railway, a suspended electric conductor arranged along the railway, a traveling car having its body supported on springs, an electric motor supported on and coupled with each axle, an upwardly-extending collector supported on the car-body, electric motor-circuits leading from the collector to each of the motors, and regulating devices arranged on the end of the car-body for controlling the current flowing through the motor. 80
7. The combination of a railway, an electric conductor extending along the railway and at a considerable elevation, a car, an electric motor supported on the axle, an upwardly-extending collector-arm supported by the car-body, a contact device carried by said arm and making a traveling contact on the under side of the conductor, motor-circuits carried on the car-body and connecting the collector with the motor, and a current-regulator to control the current in said motor-circuit. 85
8. The combination of a railway, an electric conductor extending along the railway and at a considerable elevation, a car having its body supported on the axles by springs, an electric motor supported on the axle and positively connected thereto independently of the car-body, an upwardly-extending collector-arm supported by the car-body, a contact device carried by said arm and making a traveling contact on the under side of the conductor, flexible motor-circuits carried on the car-body and connecting the collector with the motor, and a current-regulator to control the current in said motor-circuit. 90
9. The combination of a railway, an electric conductor extending along the railway and at a considerable elevation, a car, an electric motor supported on the axle, an upwardly-extending collector-arm supported by the car-body, a contact device carried by said arm and making a traveling contact on the under side of the conductor, motor-circuits carried on the car-body and connecting the collector with the motor, and a current-regulator to control the current in said motor-circuit. 95
10. The combination of a railway, an electric conductor extending along the railway and at a considerable elevation, a car, an electric motor supported on the axle, an upwardly-extending collector-arm supported by the car-body, a contact device carried by said arm and making a traveling contact on the under side of the conductor, motor-circuits carried on the car-body and connecting the collector with the motor, a current-regulator to control the current in said motor-circuit, a lighting-circuit on the car in electrical connection with the motor-circuit, electric lamps in said circuit in parallel with the motor, and means to control the current in said lighting-circuit. 100
11. The combination of a railway, a suspended conductor extending along said railway, a car having a car-body supported on springs, an upwardly-extending collector-arm supported by the car-body and provided with a contact device on its free end for making an under contact with the conductor, a frame supported on the axles independent of the car-body, a motor supported thereby and mechanically connected with the axle, and a motor-circuit carried by the car and connecting the collector with the motor, with provision to permit the rise and fall of the car-body without interrupting the motor-circuit. 105
12. The combination of a railway, a suspended conductor, a car, a collector-arm supported by the car, with provision for vertical movement, a contact device carried on the free end of the collector-arm, making an under moving contact with the conductor, an electric motor on the axle and independent of the collector-arm, and a motor-circuit between the collector and motor. 110
13. The combination of a railway, a suspended conductor, a collector formed of an arm extending upward and making an under contact with the conductor, a motor supported on an axle and adapted to rotate the wheels thereof, an elastic connection or frame between the collector and motor or axle, whereby while the motor has a fixed distance above the rails the collector may rise and fall, and an electric circuit connecting the collector with the motor. 115
